ORLANDO L. MIDDLETON, OF CLARKSVILLE, MISSOURI, ASSIGNOR OF ONE-HALF TO
WILLARD B. MIDDLETON, OF BOWLING GREEN, MISSOURI.

AEROPLANE.

Application filed April 22, 1927. Serial No. 185,752.

My invention relates to aeroplanes and more particularly to the biplane type, although not necessarily limited thereto, and it is a distinct and practical improvement to 5 overcome certain practical objections to, and defects in the present type of aeroplanes, and, has for an object to provide means whereby air pressure sets up a sustaining or 10 buoyant force to maintain the stability of the aeroplane while in descending flight should the motor go dead while in flight and to materially retard its speed.

A further object of the invention is to provide tail flaps which will all automatically 15 open by air pressure to retard the speed of a falling aeroplane which has gone into a tail spin.

With the above and other objects in view, the invention consists in the novel features 20 of construction, arrangement and combination of parts hereinafter more fully described and finally pointed out in the claims hereto appended.

Referring to the accompanying drawings 25 forming a part of this specification, wherein like characters of reference denote similar parts throughout the several views:

Fig. 1, is a top plan view of an aeroplane embodying the features of my invention with 30 portions thereof broken away and with portions thereof in sectional elevation.

Fig. 2, is a side elevation of the aeroplane with the upper and lower wings removed and showing the wing ribs in sectional elevation.

Fig. 3, is a longitudinal vertical sectional elevation of the aeroplane.

Fig. 4, is a transverse sectional elevation of the aeroplane.

Fig. 5, is a rear elevation of the aeroplane with the tail box flaps in open position such as they assume when the aeroplane develops into a tail spin.

In carrying out the aim of my present invention, I employ a suitable fuselage, or body 45 1 of the cabin type which is provided with a forward motor housing or cowl 2 in front of which housing is positioned a propeller 3 driven by means of a suitable motor, not 50 shown.

Suitably connected to the sides and top of the fuselage 1 are a pair of suitable upper wings 4 and connected directly to the sides of the fuselage 1 are a pair of lower wings 5. 55 The upper and lower wings are intercon-

nected by means of a plurality of strut members 6. The upper wings extend beyond the front and rear edges of the lower wings, as will be apparent from Fig. 1, likewise the upper wings 4 extend beyond the side edges 60 of the lower wings 5, as will be apparent from Figs. 4 and 5.

The wing fabric of the lower wings comes short of the sides of the fuselage 1 to provide updraft air passages 7 between the lower wing ribs 8 and the sides of the fuselage 1 are each provided with a plurality of elongated air passages 9 which are disposed adjacent the upper edge of the sides of the fuselage just below the upper wings 4 and these sides are also provided with a plurality of aligned elongated air passages 10 relatively larger than air passages 9 which latter passages are disposed below the upper passages 9. 75

Secured to the upper wings 4 above the fuselage 1 is a fabric covered reinforcing crown sheet 11 which is provided with a plurality of air outlet openings 12 for gradually allowing the escape of air from the interior 80 of the fuselage 1.

From the foregoing description, it is evident that should the motor go dead in flight, that in descending there would be an upward rush of air currents through passages 85 7 and also from around the front and rear edges of the lower wings 5 which would bank against the upper wings 4 adjacent the sides of the fuselage 1 and find its way through the side wall passages 9 and 10 of the fuselage and into the interior of the fuselage 1 from where it would gradually escape through the air outlet openings 12 in the top 11 of the fuselage 1 thereby tending to maintain a condition of stability of the aeroplane by setting up a sustaining or buoyant force to automatically stabilize the aeroplane 90 while descending by offering sufficient resistance to materially retard the speed of the descending aeroplane where it is glided to 100 earth at a slight angle to the horizontal. This passage of air upwardly through the lower wings and through the side wall of the fuselage and into the same is restricted in its escape through the top of the fuselage 105 and has thereby a tendency to create a buoyant effect upon the aeroplane and cause the same to descend similar to a parachute offsetting any particular ill disturbance set up by having the motor stall while in flight. 110

The aeroplane is provided with the vertical rudder 13 pivotally connected as at 14 to the open rear end of the skeleton tail box section 15 of the fuselage 1 to provide a control surface used for steering in a horizontal plane. The action of the rudder 13 is manually controlled through the lever 16 having a cable connection 17 with cross-head 18 which is fixed to the pivot member 14.

The tail box section 15 has free communication with the interior of the fuselage and it is provided with the upper and lower openings 19 and 20 which are kept normally closed by means of the upper and lower flaps or elevators 21 and 22, respectively, which flaps have hinged connections 23 and 24, respectively, with the end wall of the fuselage or body 1 to provide control surfaces used for maintaining longitudinal equilibrium and for ascent and descent respectively. The upper and lower tail box flaps 23 and 24 are manually controlled through the levers 25 and 26, respectively, having cable connections 27 and 28 with the flaps 23 and 24, respectively. The tail box section 15 is further provided with the left and right side wall openings 29 and 30 which are kept normally closed by means of the left and right tail box flaps 31 and 32, respectively, which flaps have hinged connections 33 and 34, respectively, with the end wall of the fuselage, or body 1 to provide lateral control surfaces used for maintaining lateral balance. The left and right tail flaps 31 and 32 are manually controlled through the levers 35 and 36, respectively, having cable connections 37 and 38 with the flaps 31 and 32, respectively, for maintaining lateral balance and for assisting the rudder in changing the lateral direction of flight of the aeroplane.

In case the aeroplane develops into a tail spin from any cause, the air pressure in the descending of the machine will cause the four tail box flaps to automatically open causing the inrush of air currents through the openings of the tail box and from there into the fuselage from where it can only escape gradually through the side wall openings 8 and 10 and the ceiling openings 12 which will set up a sustaining and buoyant force to retard the tail spin speed of the aeroplane, thus causing the aeroplane to descend similar to a parachute due to the fact that the fuselage has been filled with air which can only escape gradually therefrom.

I do not wish to be understood as having limited myself to the exact details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such

changes, or modifications, as may fairly fall within the scope of the appended claims when fairly construed.

What I claim is:

1. In an aeroplane structure, a cabin like fuselage having air inlet passages in the side walls and air outlet openings in the top wall thereof, upper wings and lower wings having air inlet passages therein adjacent the side walls of the fuselage. 70

2. In an aeroplane structure, a cabin like fuselage having air inlet passages in the side walls and air outlet openings in the top wall thereof, upper wings and lower wings having air inlet passages therein adjacent the side walls of the fuselage, said wings and fuselage air inlet passages and said fuselage air outlet openings all being so arranged as to admit air into the fuselage more readily than its escape therefrom to set up a sustaining or buoyant force tending to maintain the stability of the aeroplane in descent when the motor has gone dead in flight and effect a parachute landing of the aeroplane. 85

3. In an aeroplane structure, a cabin like fuselage having air inlet passages in the side walls and air outlet openings in the top wall thereof, upper wings and lower wings having air inlet passages therein adjacent the side walls of the fuselage, a tail box extending rearwardly from the fuselage, a cable controlled rudder carried thereby, said tail box having top, bottom and side wall openings therein, and hingedly supported flaps for normally closing said tail box openings. 90

4. In an aeroplane structure, a cabin like fuselage having air inlet passages in the side walls and air outlet openings in the top wall thereof, upper wings and lower wings having air inlet passages therein adjacent the side walls of the fuselage, a tail box extending rearwardly from the fuselage, a cable controlled rudder carried thereby, said tail box having top, bottom and side wall openings therein, and hingedly supported flaps for normally closing said tail box openings, said flaps adapted to be automatically opened by air pressure in case of a tail spin thereby providing spread control surfaces and causing the rush of air into the tail box and into the fuselage therefrom from where it gradually escapes through the side wall passages and top wall openings setting up a sustaining or buoyant force tending to retard the descending speed of the aeroplane and effect a parachute landing. 115

5. In an aeroplane structure, a cabin like fuselage having upper and lower wings, said fuselage having its side walls provided with a plurality of air passages and having its top wall provided with a plurality of air outlet openings, a tail box extending rearwardly from said fuselage and having its top, bottom, side and end walls provided with openings, a rudder extending into the rear open- 125

ing, and tail flaps normally closing the top, bottom and side openings of the tail box, said flaps being manually controlled to change the direction of flight and automatically opened when the aeroplane develops into a tail spin to provide control surfaces to all sides of the tail box tending to set up a retarding action to the speed of the falling plane and permit air to pass through the tail box and into the fuselage from where it escapes gradually thereby setting up a sustaining and buoyant force to retard the speed of the aeroplane while in a tail spin and to effect a parachute landing thereof.

6. In an aeroplane structure, a cabin like fuselage, upper wings, lower wings having openings therein adjacent the side walls of the fuselage, said fuselage having a plurality of openings in its side walls and having a plurality of openings in its top wall, a tail box having communication with the interior of the fuselage and having its top wall, bottom wall, side walls and its rear end wall each provided with an opening, a rudder pivotally supported at one end in the rear end opening of the tail box and hinged flaps for the top, bottom and side wall openings of the tail box.

7. In an aeroplane structure, a cabin like fuselage, upper wings, lower wings having openings therein adjacent the side walls of the fuselage, said fuselage having a plurality

of openings in its side walls and having a plurality of openings in its top wall, a tail box having communication with the interior of the fuselage and having its top wall, bottom wall, side walls and its rear end wall each provided with an opening, a rudder pivotally supported at one end in the rear end opening of the tail box, hinged flaps for the top, bottom and side wall openings of the tail box, means for controlling the movement of said rudder and means for normally controlling the movement of said tail box flaps but permit of being automatically opened by air pressure when the aeroplane descends in a tail spin to provide spread control surfaces.

8. In combination with a fuselage, a tail box extending rearwardly from the fuselage, said tail box having top, bottom and side wall openings, flap members hingedly connected at their inner ends to the fuselage for normally closing said top, bottom and side wall openings, said flap members being manually controlled to change the direction of flight and automatically opened when the aeroplane develops into a tail spin to set up a retarding action to the speed of the falling aeroplane.

In testimony whereof I have hereunto affixed my signature.

ORLANDO L. MIDDLETON.
